FOREIGN PATENT DOCUMENTS

CN 308674615 * 6/2024

Primary Examiner — Paula Allen Greene(74) *Attorney, Agent, or Firm* — Michael Best and
Friedrich LLP(57) **CLAIM**

The ornamental design for a headphone as shown and described.

DESCRIPTION

FIG. 1 is a front, bottom, right perspective view of a headphone showing my new design;
 FIG. 2 is a rear, top, right perspective view thereof;
 FIG. 3 is a rear, bottom, right perspective view thereof;
 FIG. 4 is a front elevational view thereof;
 FIG. 5 is a rear elevational view thereof;
 FIG. 6 is a right side elevational view thereof; and
 FIG. 7 is a bottom plan view thereof; and,
 FIG. 8 is a partially enlarged front, bottom, right perspective view thereof along the lines 8-8 and 8'-8' of FIG. 1.
 The broken lines illustrating portions of the headphone form no part of the claimed design. The dot-dash broken lines defining boundaries of the claimed design form no part of the claimed design.

1 Claim, 8 Drawing Sheets(56)
